UNITED STATES PATENT OFFICE

CHARLES HORTON, OF RIDGEFIELD PARK, NEW JERSEY, ASSIGNOR, BY MESNE ASSIGNMENTS, TO PILOT RADIO & TUBE CORPORATION, OF BROOKLYN, NEW YORK. A CORPORATION OF DELAWARE

STRAIGHT-LINE FREQUENCY CONDENSER

Application filed July 14, 1925. Serial No. 43,623.

This invention relates to improvements in condensers, more particularly to variable condensers adapted for application as tuning means in a radio communication.

At the present day, variable condensers have the property of varying capacity directly according to the displacement and the degree of movement of the condenser plates with respect to the fixed condenser plates, whether the movement of the condenser plates be sliding or rotating, depending upon the type of condenser. These types of condensers produce a straight line function as regards the capacity plate displacement curve and the parabolic function as regards the wave length plate displacement curve.

Some variable condensers have been formed with cut out rotor plates with the result that the wave length scale is spread so that the capacity varies as to the square of the deflection and the wave length is uniform along the entire length. However, this form produces bunching of stations along portions of the dial, and practically prevents the reception of stations having low wave lengths, along the lower portion of the dial.

Up to date, there has been a tendency in radio reception tuning condensers to produce a straight line frequency device which as at present indicated, consists of a cut out rotor placed off center from the stator, which form of condenser will give a parabolic curve for the capacity plates displacement calibration curve, which curve lies parallel to the abscissa axis with a sudden change of slope of the curve merging at its upper end to a slope parallel to the ordinate axis. This form of condenser produces a straight line frequency plate displacement curve but in general has the inherent difficulty of being cumbersome and unwieldly in operation and rather large in size. The shape of the plates in such condenser are usually in the form of long narrow propeller-like sections which are placed considerably off center and as a result thereof produce a bulky instrument.

It is the purpose of this invention to provide a condenser wherein the stator plate is cut out, together with the rotor plate, both of which are centered with respect to one an-

other and have formed thereon reciprocal cut out portions so that the plates are symmetrical and in inverse arrangement.

In this manner a curve is produced which is a straight line frequency dial displacement calibration curve; and a gradually sloping capacity displacement curve having a configuration substantially parallel to the abscissa for a period equivalent to 40 as registered on the plate displacement dial, and at the same time having a sudden incline between 40 to 90 in the capacity curve with respect to the plate displacement and then a slope in the capacity curve substantially parallel to the ordinate axis from 90 to 100.

This form of condenser will function as a straight line capacity condenser having a maximum of three percent and operating independently up to 40 on the 100 scale; subsequently, the condenser will operate as a straight line frequency condenser acting from 40 to 90 on the 100 scale; and at the same time having a maximum of 47%; and lastly, will operate as a straight line capacity condenser acting from 90 to 100 with a 50% maximum.

In this manner the particular form of condenser has been produced which will have a straight line frequency plate displacement curve and yet at the same time produce a variable capacity plate displacement curve wherein the beneficial effects of the straight line capacity and straight line frequency functions of the condenser are introduced. In other words, by the use of these particular cut out stator and rotor elements wherein the curves in these elements are reciprocal and inversely symmetrical to one another it is possible to produce a more efficient and more simple and more effective condenser element for tuning in radio reception circuits.

The particular advantage gained by the use of a symmetrically cut rotor and stator plate, both centered with respect to one another, is that the stations now in use, those from 400 to 600 meters, will be bunched more or less regularly at the upper end of the dial, that is say from 50 to 100, whereas room will be left for the reception of new low wave length stations which are bound to come in the future, at the lower end of the dial. A

more thorough explanation of this will be given in the consideration of this invention as it progresses in the description.

Among the objects of the invention it is aimed to provide a particular form of condenser wherein the rotor and stator plates are cut out so as to provide inverted symmetrical curves which cooperate with one another to produce a straight line frequency plate dis-
10 placement calibration curve and which, due to their particular configuration eliminate the necessity of positioning the stator and rotor plates off center with respect to one another; to provide a form of condenser wherein the
15 minimum of metal is used for the rotor and stator elements; to provide a plurality of co-operating portions in the respective stator and rotor elements which will co-act to form different types of curves at respective differ-
20 ent displacement positions of the dial controlling the movement of the rotor plates; and to provide a simple and yet more effective form of condenser of the straight line frequency type.

25 Specifically, it is aimed to provide a condenser in which the rotor and stator plate elements have cut out portions whereby considerable metal heretofore not producing any active function, is eliminated. Further it is
30 aimed to provide a plurality of co-acting elements, one movable and one stationary, cut out so as to have curved surfaces symmetrical but inversely positioned from one another.

Still further it is aimed to provide a con-
35 denser of the straight line frequency type having movable and stationary plates centered with respect to one another.

Still further it is aimed to provide a novel form of cut out rotor and stator plates
40 wherein sections of the plates cooperate with one another during partial rotation of the dial controlling the movable plates, while other portions of said plates cooperate with one another simultaneously with the first
45 named sections of the plates upon further rotation of the dial.

Still further it is aimed to provide for the distribution of the stations in a radio reception device so that the present wave lengths, from 400 to 600 meters, will be positioned at the upper end of the dial and room will be provided for a series of stations of low wave lengths, say 50 to 150, at the lower end of the dial.

55 These and other advantages, capabilities and features of the invention will appear from the subjoined detailed description of one specific embodiment of the invention as illustrated in the accompanying drawings in which,

Fig. 1 is a side elevation in section of the condenser element.

Fig. 2 is a front view of the condenser ele-
60 ment including the plates.

Fig. 3 is a front elevation of one form of rotor and stator plates.

Fig. 4 is a front elevation of a modified form of condenser plates.

Fig. 5 is a front elevation of a still fur-
65 ther modification.

Fig. 6 is a graphical representation of the frequency plate displacement characteris-
70 tics of the condenser.

Fig. 7 is a graphical representation of the capacitance plate displacement of the con-
75 denser, and

Fig. 8 is a diagrammatic representation of the changed reception diagram caused by the
80 use of the new condenser.

Referring more particularly to the refer-
ence characters in the drawing; numeral 1
85 represents the panel on which the condenser is adapted to be fastened by means of posts 2 positioned along the outer portion of the end plate 3, which end plate cooperates with a second end plate 4 for containing therein the movable and fixed elements of the condenser.

Referring particularly to Figs. 1 and 2;
the condenser element consists of the shaft
90 element 5 passing through the panel 1 and
having the dial member 6, at its outer extremity, which shaft element is supported in bearings 7 and 8 formed on the end plate mem-
95 bers 3 and 4. A series of movable plates 9
are fixed on the shaft 5 and held firmly there-
on by means of washers 10 herein shown as
partly hexagonal and partly cylindrical in
shape, the end washers being formed as he-
99 gagonal nuts to position the movable plates
9 with respect to the end plates 3 and 4.

A lug 11 is formed on the washer end 10, for contacting with a plurality of stop mem-
105 bers 12 for limiting the rotation of the mov-
able plate members 9 only one of which stop
members is herein shown, the other being
exactly 180 degrees apart. A plurality of
110 fixed stator plates 13 are positioned within
the end plate members 3 and 4, which fixed
plates are supported at their end extremi-
ties on spindles 14 fastened to non-metallic
115 insulating plates 15, which plates are at-
tached on each side of each end plate by
means of rivets 16 and a fixed spindle mem-
ber 17 respectively. As is noted in Figs. 2
120 to 5, the fixed stator plates have a support at
their end extremities only, though the means
of support can be varied without departing
from the scope of disclosure indicated by the
invention. So far the description has been
125 limited to the ordinary form of condenser. In
other words, the structural details of the
position of the respective condenser plate
elements which form the subject matter of
the invention has been indicated in their well
known positions in the condenser proper.

Referring particularly to Figs. 2 to 5 here-
in: it should be noted that the configuration
of the respective rotor and stator plate ele-
130 ments indicated as 9 and 13 respectively form

the essence of this invention. It is noted in Fig. 3 that the rotor element 9 is pivoted about the shaft member 5, the said rotor element being positioned centrally thereof and being formed of an aluminum blank having a plurality of cut out spaces 18 and 19 respectively so that the shape of one side, that is, the right side of the condenser element with respect to its metallic portion is like a V whereas the left handed portion of the condenser element is of V shape with a connecting link 20, extending between the center and the extremity of said plate. The stator plate 13 is shown as having a plurality of cut out portions 21 and 22 respectively, of which the portion 21 is symmetrical to the cut out portion 18 but positioned in reciprocal relation thereto so that the two curves 23 and 24, formed by cutting out the rotor and stator plates, are reciprocally symmetrical to one another. As the rotor plate 9 in Fig. 3 is turned in a clockwise direction toward the stator plate 13 the period of the inductive contact between the rotor and stator plates is limited to the extent of co-action of the curve surfaces 23 and 24 with each other.

Referring particularly to Fig. 4: it is noted that the rotor plate has a cut out portion 25 at the right hand side thereof to form the V at the right of the center thereof, and similarly the stator plate 13 has a cut out portion 26 symmetrical to and oppositely or reciprocally disposed of said cut out portion 25 of the rotor plate so that the curve portion 27 of the rotor plate will form a curve reciprocal to and symmetrical with the curve 28 with which it co-acts as the rotor plate is moved to the right by the actuation of the dial member 6.

Referring particularly to Fig. 5: wherein a modification of the invention is shown, it is noted that the rotor plate 9 and the stator plate 13 have cut out sections 29 and 30 which are symmetrical with and positioned in inverse relation with respect to the cut out portions 31 and 32 of the stator plate so that the plate sections 33, 34, 35 and 36 respectively are reciprocally symmetrical to one another. However, a portion of the condenser plate is formed about the shaft member 5 about which the movable plate is pivoted, which portion 37, consisting of a plurality of oppositely extending wings or fins, cooperates with the wings or fins of the U shaped projection 38, extending upwardly from the base of the stator member. In this manner as the rotor plates 9 are actuated by the dial member 6, the arms of the projection 37 of the rotor first co-act with the arms 38 of the stator plate for a considerable period of rotation of said dial member on the shaft 5 to which it is attached which period is equivalent to an arc of about forty percent of the total rotation of the rotor plate and at the same time, produces a straight line capacitance curve capable of bringing in stations at the low wave lengths.

As the rotor plate is further actuated in a clockwise direction, the portion 33 of the rotor plate cooperates with a co-acting portion 34 on which portions the curves are reciprocally symmetrical to bring in the stations with higher wave lengths at a straight line frequency action.

The further rotation of the rotor plate 9 will cause the portion 33 to cooperate with 70 32, and 35 to cooperate with 34, which arc 75 rotation is within 40 to 90 percent of the total rotation of the dial 6.

As the dial is rotated from 90 to 100 percent of its total arc of movement, the second wing 37' of the rotor plate cooperates with the wing 38 of the stator plate, whereas the first wing 37, of the rotor plate cooperates with the second wing 38' of the stator plate. In this manner a straight line capacity function is introduced into the capacity curve of 80 85 the condenser as shown in Fig. 7. However, at the same time, the frequency characteristics are that of the straight line frequency curve as shown in Fig. 6.

Referring particularly to Fig. 8, it should 90 be noted that by the application of this particular form of cut out rotor and stator that the applicant has been able to bunch all of the stations with a wave length of 400 to 600, at the upper end of the dial, whereas, previously they had been bunched at the lower end of the dial as shown in the calibrated dial 40. In the new calibration dial 41 the lower portion thereof is open for the positioning 95 therein of new stations operating on low 100 wave lengths.

It is obvious that various changes and modifications may be made to the details of construction without departing from the general spirit of the invention as set forth in the 105 appended claims.

What I claim is:

1. In an electric current controlling instrument, in combination with a series of W-shaped stator plates, rotor plates of similar shape co-acting with said stator plates, the inner edge of the arm portions of said rotor plates being adapted to coincide with the inner edges of the arm portions of the stator plates, means for actuating said rotor plates, 110 115 projections at the central portion of said rotor and stator plates, which projections cooperate with one another, prior to the cooperation of the remaining portions of said stator and rotor plates.

2. In an electric current controlling instrument, the combination with a series of stator plates having cutout portions, whereby to form a plurality of outwardly extending arms, projections extending outwardly 120 125 from the center portion of said stator plates, and rotor plates symmetrical to and movable with respect to said stator plates, the edges of the arm portions adjacent the cutout portions of said stator and rotor plates being 130

adapted to coincide upon movement of said rotor plates.

3. In an electric current controlling instrument, the combination with a series of 5 stator plates having cutout portions, whereby to form a plurality of outwardly extending arms, projections extending outwardly from the center portion of said stator plates, rotor plates symmetrical to and movable with respect to said stator plates, the inner edges of 10 the adjacent cutout arm portions of the rotor and stator plates being adapted to coincide upon movement of said rotor plates, said projections in the central portion of said plates 15 being adapted to cooperate prior to the arm portions of said plates.

4. A variable condenser having rotor and stator plates cooperating with one another, said rotor and stator plates having cutout 20 portions, thereby providing curved edges of arm portions adjacent the cutout portions, the said curved edges of said arm portions being adapted to coincide with one another during movement and upon complete dis- 25 placement of the rotor plates.

5. In an electric current controlling instrument, the combination with a series of 20 stator plates consisting of a plurality of outwardly extending arms, and a plurality of fins extending outwardly of the center portion of said plates, the area between the arms and the fins being cut out, of a plurality of 25 rotor plates having cutout portions symmetrical to that of the stator plates.

6. In an electric controlling instrument, the combination with a series of rotor plates, having a body portion disposed centrally thereof, and arms extending outwardly from each side thereof, in the form of segments of 30 a circle, a shaft member attachable centrally of said rotor plates for rotating the same, stator plates symmetrical to said rotor plates, said rotor plates being adapted to coincide with said stator plates upon the actuation 35 thereof, projections extending outwardly from the center portion of said stator and rotor plates, whereby the projections of the respective rotor and stator plates will co-act with one another prior to the co-action of 40 the arms of said plates.

7. In electric controlling instruments, the combination with a plurality of stator plates having each a shank portion, and a plurality of curved arms extending in opposite directions therefrom, projections extending outwardly from the center portion of said shank portion and parallel to said arm portion, rotor plates of formation similar to said stator plates, and having each apertures disposed centrally of said shank portion, a shaft member passing through said apertures for rotating said rotor plates, whereby the curved arms of said rotor plates coincide with the curved arms of said stator plates at the extremitiy of movement thereof, whereby upon 45

rotation of the shaft, the projections of the stator plates coincide with the projections of the rotor plates, prior to the co-acting of the arms of the rotor and stator plates.
